(57) **CLAIM**

The ornamental design for a golf grip cap, substantially as shown and described.

DESCRIPTION

FIG. 1 is a perspective view of the golf grip cap;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof;
 FIG. 7 is a bottom plan view thereof;
 FIG. 8 is a perspective view of a second embodiment of the golf club cap;
 FIG. 9 is a front elevational view of FIG. 8;
 FIG. 10 is a rear elevational view of FIG. 8;
 FIG. 11 is a left side elevational view of FIG. 8;
 FIG. 12 is a right side elevational view of FIG. 8;
 FIG. 13 is a top plan view of FIG. 8; and,
 FIG. 14 is a bottom plan view of FIG. 8.
 The broken line showing is included for the purpose of illustrating and forms no part of the claimed design.

1 Claim, 6 Drawing Sheets(56)
